DESIGN FOR A SHOE

David R. Brady, Highland Park, Mich., assignor
to David R. Brady and J. Windsor Davis, joint
trustees for the Brady Research Company, De-
troit, Mich., a joint-venture company

Application May 25, 1940, Serial No. 92,590

Term of patent 14 years

To all whom it may concern:

Be it known that I, David R. Brady, a citizen
of the United States, residing at Highland Park,
in the county of Wayne and State of Michigan,
have invented a new, original, and ornamental
Design for a Shoe, of which the following is a
specification, reference being had to the accom-
panying drawing, forming part thereof.

Figs. 1 and 2 are opposite side elevations of a
shoe, showing my new design, and

Fig. 3 is a rear elevation of the same.

The essential features of my design reside in
the part shown in full lines and consist of a
counter of the specific configuration as illus-
trated, the same being attached on the outer
side of the heel of the shoe.

I claim:

The ornamental design for a shoe, substan-
tially as shown and described.

DAVID R. BRADY.
